UNITED STATES PATENT OFFICE.

THEODORE U. CARGILL, OF WASHINGTON, DISTRICT OF COLUMBIA.

BUILDING-BLOCK MOLD.

Application filed June 2, 1921. Serial No. 474,411.

To all whom it may concern:

Be it known that I, THEODORE U. CARGILL, a citizen of the United States, residing at Washington, District of Columbia, have invented certain new and useful Improvements in Building-Block Molds; and I do hereby declare the following to be a full, clear, and exact description of the invention, such as will enable others skilled in the art to which it appertains to make and use the same.

The present invention relates to building block molds, and aims to provide a novel and improved mold for the production of building blocks from concrete or other plastic material, and including sections which can be readily assembled and taken apart in molding the blocks.

Another object is the provision of a novel mold for forming plastic building blocks with end recesses to provide spaces between and within the adjacent end portions of the blocks when laid end to end, for the flow of air therethrough and to render the wall composed of the blocks a better insulator of heat and cold.

A further object is the provision of a block mold comprising sections having novel means for assembling and fastening them together and enabling the sections to be readily separated after the concrete has set, without danger of breaking the block.

With the foregoing and other objects in view, which will be understood as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a plan view of the main mold for making a block of N or Z shape for building purposes.

Fig. 2 is an end view thereof.

Fig. 3 is a side elevation, showing a portion in section.

Fig. 4 is a cross section on the line 4—4 of Fig. 1.

Fig. 5 is a plan view of a modified form of mold for producing a corner block.

Fig. 6 is a plan view of another modified form of mold for producing an end of half block.

Fig. 7 is a plan view of still another form of mold.

The mold shown in Figs. 1, 2, 3, and 4 is for the production of the main building block, which is of N or Z shape, and such mold comprises a pair of duplicate sections composed of sheet metal. Each mold section comprises a sheet metal strip disposed on edge, and bent to provide the side wall 11, spaced end wall portions 12 and 13 and the inner walls 14 and 15 converging from the portions 12 and 13. The wall 15 is parallel with but shorter than the side wall 11, and the wall 14 extends obliquely between the portion 12 and inner end of the wall 15. The portion 12 extends between the adjacent ends of the walls 11 and 14.

When the two sections are disposed in reversed positions with the ends of the strips together, and the walls 11 and 15 confronting one another as well as the walls 14, the space between such walls surrounded by the sections is of N or Z shape, as seen in Fig. 1. The walls 14 and 15 of each section provides a reentrant angle to form a recess of corresponding shape in the end of the block. The lower edges of the walls 14 and 15 have flanges 16 bent toward one another to stiffen said walls and prevent them from bending under pressure against same from within in the mold.

In order to close the space of each mold section between the walls 14 and 15, a top plate 17 of triangular form is fitted between the upper edges of said walls and is secured thereto, such as by means of a downturned flange 18 extending along the edges of the plate 17 and riveted or otherwise secured to the walls 14 and 15. The top plates 17 of the mold sections are preferably flush with the upper edges of the walls and will prevent the concrete or plastic material from spilling between the walls 14 and 15 when being poured or dumped into the mold. Said plates 17 will also strengthen the sections, and form webs between the walls 14 and 15 rigidly uniting or connecting them.

The ends of the strips from which the mold sections are bent, are provided with portions to engage one another, to prevent the side walls 11 from springing outwardly under the pressure from within the mold. Thus, as shown, the ends of the walls 11 opposite to the corresponding end wall portions 12 have tongues or projections 19 extending therefrom, to pass through slots

20 in the end wall portions 13 of the opposite sections, when the sections are slid together longitudinally. The portions 13 have the extensions 21 adjacent to the slots 5 20, and the outer edges of the portions 13 are otherwise flush with the outer surfaces of the walls 11. The tongues 19 in passing into the slots 20, will prevent the side walls 11, from springing away from the inner 10 walls 15.

Means are provided at the diagonally opposite corners, where the terminal portions of the sections are interengaged, for fastening the sections together against accidental 15 separation. Thus, keepers 22 are riveted or otherwise secured to the side walls 11 and project from those ends thereof opposite to the corresponding portions 12 to extend across the outer edges of the portions 13 of 20 the opposite sections, and said keepers 22 have notches 23 for receiving latches 24 pivoted, as at 25, to the portions 13. After the sections are assembled to move the tongues 19 into the slots 20 and the keepers 25 22 across the edges of the portions 13, the latches 24 are swung down into the notches 23, and by cam action in said notches, will tightly clamp the portions 13 in abutment against the ends of the walls 11. This will 30 secure the sections tightly together.

In order to face the opposite sides of the block, or to form the surfaces of the sides of the block with any suitable or desired 35 impressions, for purpose of ornamentation or appearance, die plates 26 are secured to the inner surfaces of the side walls 11 by means of screws 27, or the like, and their inner exposed surfaces can be ribbed or otherwise formed to make impressions in 40 the opposite sides of the block accordingly. These plates 26 can be readily removed to be replaced by others, and plates having different styles of die impressions can be used interchangeably. When the material is 45 poured into the molds and rammed or packed therein, it is pressed tightly against the plates 26, to form the side surfaces of the block accordingly.

In using the mold, when the sections are 50 assembled and secured, they can be seated on a table or other surface and the plastic mixture poured into the molds and rammed or packed tightly therein, such material being levelled off flush with the upper edges 55 of the sections. After the material has set, the latches 24 are disengaged from the keepers 22, and two sections, after being moved longitudinally apart a short distance, to withdraw the tongues 19 from the slots 20, can then be separated easily. The block will 60 remain seated on the table or surface, and will be of N form, having the recesses in the opposite ends thereof, whereby when the blocks are laid end to end, the recesses 65 65 register and form spaces through which

the air can flow upwardly in the wall. The opposite side portions of the block are connected by a diagonal web or portion.

Fig. 5 shows a mold for making the corner blocks. The corner block has one end 70 closed where it is exposed at the corner of the building wall or at the end or edge of such wall. The mold comprises two sections, and one section is similar in shape to the sections of the mold above described, 75 and includes the side wall 11' which is slightly longer than the side walls 11, spaced end wall portions 12' and 13' and converging inner walls 14' and 15'. The other section is of angular or L shape, and 80 includes a side wall 11'' and the end wall 13''. The end wall of the second section does not have the reentrant portion, but is straight across the end of the mold, to form the block accordingly. A triangular core 85 shell 28 is disposed within the mold with its three sides parallel with and spaced from the walls 11', 14' and 13'', to form an opening in the block. This shell 28 has an upper plate or web 29 similar to the plate 90 or web 17' secured to and located between the upper edges of the walls 14' and 15'. Said plates or webs strengthen the structure and also prevent the material from dropping down between the inner walls outside 95 of the mold space. The block is of substantially the same form as the N shaped block, with the exception that the block has one end closed. Die plates 26' are also secured to the walls 11', 11'' and 13'' to form 100 the surfaces of the side and end walls of the block accordingly, and the terminals of the two sections are secured together in the same manner as hereinbefore described.

Fig. 6 shows a mold for making a U or 105 half block to be used at the ends or edges of a wall, with the ends of the blocks flush. This mold also comprises two sections. One section includes the side wall 30 and end wall 31, and the other section includes the 110 opposite side wall 32, end wall portions 33 and 34, and inner walls 35, 36 and 37 spaced from and parallel with the respective walls 32, 31 and 30. Die plates 26'' are secured to the walls 30, 31 and 32 at the inside to 115 form the surfaces of the side and end walls of the block, and the sections of the mold are secured together in the same manner as hereinbefore described.

Fig. 7 shows still another form of mold 120 for making a corner block, and each section of the mold has a side wall and an end wall. One section has the side wall 110 and an end wall 120 having the reentrant portion 140 with a top plate or web 170, and the 125 other section has the side wall 111 and an end wall 121, the side wall 111 having a reentrant portion 141 with a top plate or web 171. The opposite ends of the sections are connected as hereinbefore described, and 130

the walls 110 and 121 have the plates 260 at the inside for finishing one side and one end of the block. The opposite side and end of the block are formed with recesses 5 where they match the companion blocks.

Having thus described the invention, what is claimed as new is:—

1. A building block mold comprising sections of angular form including walls arranged at angles with one another, one wall having a reentrant portion with spaced walls, and means for slidably connecting said sections and securing them together and so arranged that the section having the

reentrant portion can be slid longitudinally 15 of such portion for the withdrawal of said portion from the molded block.

2. A building block mold comprising sections having side and end walls, the end walls having reentrant portions, said side 20 and end walls of the sections having portions to interengage one another when the sections are moved together longitudinally, and means for fastening the sections together.

In testimony whereof I have signed my name to this specification.

THEODORE U. CARGILL.
